ATTORNEY

UNITED STATES PATENT OFFICE.

FRANK BOWEN, OF OMAHA, NEBRASKA.

PUMP.

SPECIFICATION forming part of Letters Patent No. 618,835, dated February 7, 1899.

Application filed April 19, 1898. Serial No. 678,143. (No model.)

To all whom it may concern:

Be it known that I, FRANK BOWEN, residing at Omaha, in the county of Douglas and State of Nebraska, have invented certain useful Improvements in Pumps; and I do hereby declare that the following is a full, clear, and exact description of the invention, such as will enable others skilled in the art to which it appertains to make and use the same, reference being had to the accompanying drawings, which form a part of this specification.

This invention has relation to an improvement in pumps, the object being to provide a neat and simple device especially adapted to the use of bar-keepers, druggists, and store-keepers, and embodies a simple pump to be used in conjunction with a cask or bottle, so that the liquid therein can be quickly removed.

In the accompanying drawings I have shown in Figure 1 an ordinary bottle provided with my improvement, showing the same as used as a pump, while in Fig. 2 I show my device as used in connection with a barrel or cask, the device acting as a siphon and embodying the same.

My invention embodies, essentially, a stopper 2, preferably of rubber and of any suitable size, which is intended to be inserted into the neck of a bottle or the hole of a cask or barrel to procure an air-tight fitting. Extending through this stopper 2 is an ordinary gooseneck 8, of any suitable size or material, which below is provided with an extension 9, which may form a part of the gooseneck or be secured thereto in the form of a rubber tube. Passing through the stopper is a second tube provided with an ordinary air-bulb 7, secured thereto by means of the flexible tube 6, and positioned above the stopper is a valve 5, provided with a suitable opening 4, as is shown in Fig. 1. In place of the air-bulb 7 an ordinary pump of any construction could be used. This would embody my invention, and in order to be used in connection with a bottle, cask, or any other suitable re-

ceptacle an air-tight fitting would have to be insured, when by smartly working the air-bulb to increase the pressure within the receptacle the liquid would be promptly forced 50 out of the gooseneck, under which a tumbler or any other suitable vessel could be placed. To check the stream which will flow for a suitable length of time, it would simply be necessary to actuate the valve 5, so as to release 55 the air within the receptacle.

When my device is to be used in connection with a cask or barrel which it is desired to empty, it is simply necessary to prolong the gooseneck 8, which is done by connecting 60 to the same an ordinary section of rubber tube 10, which is permitted to enter the cask when the pump is actuated until the fluid finds an escape through the tube 10, when by promptly disconnecting the tube 6 a siphon would have 65 been created, which will run as long as the air is permitted to feed through the tube 3.

In Fig. 2 I have shown my device as being used as a siphon. The pump is especially adapted to be used in connection with a demijohn and bottles from which liquid is to be vended.

Now, having thus described my said invention, what I desire to secure by United States Letters Patent is—

The combination with a flexible stopper 2, provided with two openings, of a goosenecked tube 8 extending through said stopper, the flexible extension 9 secured to said tube 8, below the stopper, the stub-tube 3 passing 75 through said stopper, the air-bulb 7 secured to said stub 3 by means of the flexible tube 6, and the valve 5 positioned above said stopper 2, and closing the opening 4 within said stub-tube 3.

In testimony whereof I affix my signature in presence of two witnesses.

FRANK BOWEN.
